AUTOGRAPHIC REGISTER

Julius B. Schliemann, Beverly, Mass., assignor to Royal Business Forms, Inc., a corporation of New Hampshire
Filed Dec. 2, 1958, Ser. No. 777,683
4 Claims. (Cl. 282—15)

This invention relates to autographic registers which are machines commonly used in business establishments, principally for making records of sales. In the conventional machine, a plurality of overlying printed forms with carbon paper or equivalent therebetween are sequentially fed to a writing position so that a written record made on the top form will be duplicated on all of the underlying forms. After the record of the sale or transaction has been made on one set of forms, the forms are advanced in such manner that the topmost forms can be torn off for distribution while the bottommost form remains in the machine as a continuous permanent record for subsequent use by an appropriate department of the business.

One type of form that has come into common use with autographic registers is the so-called flat pack in which a plurality of superimposed continuous forms, usually three but not limited to any particular number, are appropriately printed and numbered and assembled in zigzag formation to provide a pile of continuous forms of limited number. Such a pack provides enough forms for several days business in the ordinary establishment so that reloading is not burdensome. This type of form is relatively economical, as it may be printed in small quantities and sold at a low price in comparison to the longer forms packaged in individual rolls.

Autographic registers with which folded flat packs have heretofore been used have functioned satisfactorily but have had the disadvantage of being of unduly large dimensions. This has been because of the necessity of providing a collecting bin at and beyond the discharge end of the writing table at least as large as the form. Such machines have occupied excessive space and hence many attempts have been made to provide a register of smaller dimensions. One obvious way of reducing the dimensions of such a device would be to position the folded flat pack of forms in a supply compartment located where it would be partially under the writing table and to locate the collecting bin also under the writing table instead of therebeyond. Registers made according to this general plan are to be found in the prior art. However, such machines have failed to come on the market because no means, so far as I am aware, has been developed which is capable of successfully refolding the bottommost form in a collecting bin located under the writing table. Such refolding is necessary so that when the strip of folded forms constituting the folded flat pack has been completely utilized the bottommost strip of sheets will be folded properly in the collecting bin for subsequent removal and use by the accounting or other departments of the business.

Accordingly, a principal object of the invention is to provide an autographic register having a supply compartment in which a folded flat pack of forms may be placed, a writing table above the supply compartment and over which the forms may be drawn and held in stationary position while writing is applied thereto, feeding mechanism for pulling the forms from the supply compartment to position a new set of forms at the writing table while directing the bottommost forms to a collecting bin located beneath the writing table and in which they will automatically be positioned and folded one on the other in inverted position while the upper forms are directed to an exterior position where they may be torn off for use.

2

Another object of the invention is to provide means capable of causing proper registration of each new set of forms brought to the writing table from the supply compartment. Still another object of the invention is to provide common means for advancing the forms over the writing table and for causing the bottommost form to be properly folded in the collecting bin in inverted position.

These and other objects of the invention will become more apparent as the description proceeds with the aid of the accompanying drawings in which

FIG. 1 is a plan view with a portion of the rear cover broken away to show part of the driving belts and part of the hinge of the writing table.

FIG. 2 is a vertical section taken approximately on the line 2—2 of FIG. 1.

FIG. 3 is a view similar to FIG. 2 with the form advanced one full sheet beyond the position shown in FIG. 2.

FIG. 4 is a view similar to FIGS. 2 and 3 but with the form advanced approximately one-half sheet beyond that shown in FIG. 3.

FIG. 5 is a vertical section to enlarged scale taken on the line 5—5 of FIG. 3.

FIG. 6 is a view similar to FIG. 2 drawn to enlarged scale to show in more detail the lefthand end of FIG. 2.

FIG. 7 is a fragmentary side elevation of the lefthand end of FIG. 1 showing the lid broken away and in raised position. In this view the forms have been omitted to show more clearly the relationship of the far end of the writing table and the flap.

FIG. 8 is an enlarged vertical section taken on the line 8—8 of FIG. 5 about 30 degrees before the aligning fingers have reached the end of their 360 degree movement.

FIG. 9 is an enlarged vertical section taken on the line 9—9 of FIG. 5, showing the operation of the flap that causes the uppermost sheets of the form to leave the register as the forms are advanced from the writing table.

FIG. 10 is a plan view of the flap and writing table with the lid removed.

Now referring to the several figures, the register comprises what may be referred to as an enclosed generally boxlike housing which includes therein the operating mechanism as well as the supply compartment S and the collecting bin M. There is an upper hinged lid which may be raised to permit insertion of the folded flat pack in the supply compartment S, and there is a hinged closure at the rear end of the register which may be swung away to permit removal of the folded sheets from the collecting bin M.

Referring now more particularly to the figures, the housing comprises a bottom 2 having vertical sides 4 and 6 and mounted on any suitable type of legs 8 which preferably have non-slip bottom surfaces. The housing is closed at its front end by an upwardly extending wall 10, at the top by a lid 12, and at the rear by a hinged rear wall 14. The lid 12 has depending sides 16 and 18, the terminal ends of which as at 20 and 22 are pivoted to the sides 4 and 6 by means of a transversely extending shaft 24 held in place by any convenient means such as the cotter pins illustrated.

The lid 12 when viewed from the top as in FIG. 1 has a rectangular opening 26 through which the forms of the pack are successively exposed. The forms are supported by a writing table 28 which is supported by the wall 6 and an inner intermediate wall 30 (see FIG. 10). The writing table 28 has at its lower end rollers 32 over which the forms pass as they are drawn to writing position from the supply compartment S. Shaft 33 carries the rollers 32 and also the hinges 35 of table 28. The supply compartment is in the form of a shallow rectangular tray

having a bottom 34, a back wall 36 and side walls comprising the adjacent parts of walls 6 and 30.

When the lid 12 is raised as indicated in FIG. 7, the front end of compartment S between rollers 32 and wall 10 will be exposed so that a pack of folded flat forms may be placed therein. Such a pack is suggested by the solid zigzagging lines appearing in FIGS. 2, 3 and 4. It will be understood, however, that the pack comprises a substantial number of forms. Each solid line in FIGS. 2, 3 and 4 indicates a plurality of superimposed forms with carbon paper or equivalent therebetween. The multiple forms are drawn together as a unit from the compartment S to the writing table 28. Then as the forms are again advanced upper forms indicated at A and B in FIGS. 2, 3, 4, 6 and 9 pass out of the machine to be subsequently torn off and the bottom form C is deposited in the collecting bin M.

The collecting bin M is defined by the bottom 2, a vertical front wall 38, the side walls 6 and 30 and the rear hinged wall 14. As can best be seen in FIGS. 1, 6 and 9, wall 14 is hinged to a pin 40, the ends of which are carried by walls 6 and 30.

The lid 12 at the rear end of the opening 26 terminates in a crosswise extending channel 42 which is sufficiently rigid to act as a support for the upper feed rollers. As can best be seen in FIGS. 1, 5 and 6, the channel 42 has mounted thereon three guide blocks 44, 46 and 48 with vertical slots therein such as illustrated at 50 in block 46 shown in FIGS. 2 and 6. These blocks maintain in position a transversely extending shaft 52 which carries upper feed rollers 54 and 56. The slots in blocks 46 and 48 contain compression springs 58 which bear downwardly on shaft 52 to urge the rollers 54 and 56 downwardly when the lid 12 is closed and the rollers are in operating position.

Blocks 46 and 48 are secured to channel 42 by screws 60, while block 44, which does not contain a compression spring, is secured by a pair of bolts 62. A small gear 64 is affixed to the righthand end of shaft 52 (see FIGS. 1 and 5) and this gear meshes with a larger gear 66 located inside wall 4 and mounted on shaft 68. One end of shaft 68 is carried by wall 4 and the other end by the wall 6. The intermediate portion of the shaft 68 is enlarged at 70 with hubs 72 and 74. To these hubs are bolted grooved pulleys 76 and 78 over which extend rubber driving belts 80 and 82. These belts, as can be seen from FIGS. 1, 2 and 5, also pass over a roller 84 suitably grooved as at 85 (see FIG. 6) to maintain the belts in position thereon. Roller 84 is carried by shaft 86 which is supported by walls 6 and 4. The belts also pass over a pair of idlers 88 and 90 rotatably mounted on shaft 92 and also around the underside of a second pair of idlers 94 and 96 rotatably mounted on shaft 98.

On the left end of shaft 68 there is a crank 100 having a handle 102 for manual manipulation. When crank 100 is turned counterclockwise, as viewed in FIG. 7, it is apparent that the belts 80 and 82 will be correspondingly driven by the pulleys 76 and 78. The number of teeth on the gears 64 and 66 are so related that the linear travel of the surfaces of feed rollers 54 and 56 during one revolution will equal the linear travel of the belts 80 and 82. The forms are of such length that one revolution of crank 100 will advance the forms exactly the length of one sheet.

The forms are caused to be drawn out of the supply compartment S in the following manner: After the forms are initially placed in compartment S, the top set of forms, which consists, for example, of three identical superimposed forms which for reference will be referred to as sheets A, B and C, are drawn by hand out and toward the rear of the register over the writing table 28, the lid 12 of course being raised at this time. Each of the sheets A, B and C near its advancing edge has, as shown in FIGS. 1, 5, 6 and 8, a pair of holes 104 and 106. These holes, indicated by the two short transverse

lines H—H in FIGS. 2, 3, 4 and 6, are designed to serve as aligning means acting in cooperation with a pair of fingers 108 and 110 mounted on shaft 68 and in a fixed angular relation with the pulleys 76 and 78.

5 The leading two upper sheets A and B are passed over a separating flap 112 (see FIG. 9) which is pivotally mounted on a shaft 114, the ends of which are carried by the sides 6 and 30. These two upper sheets A and B, as shown in FIG. 9, can pass beyond and above the rear of 10 the housing, moving under the transverse support 42 of the lid 12 and over the flap 112 just referred to. The bottom sheet designated C is fed to a position below flap 112 on top of belts 80 and 82 and inside the hinged rear wall 14. The fingers 108 and 110 positioned as shown in 15 FIGS. 5 and 6 will be located in the holes 104 and 106 of the three sheets A, B and C. This can be seen in FIGS. 5 and 6. The fold lines of the sheets A, B and C, as illustrated in FIG. 9 when the fingers 108 and 110 are in the positions shown in FIG. 6, will be at the locations indicated at 130. This is immediately adjacent the relatively sharp corner 132 of the tear element 134. Thus the user may readily sever sheets A and B from the following corresponding sheets A1 and B1 by tearing them off in the usual manner.

20 25 In order to limit the rotation of crank 100 to a single revolution and to cause the fingers 108 and 110 to cease their rotation at the same position at the end of each revolution, latching means is provided in the form of two outwardly extending spring pressed pins 116 and 118 30 which are mounted in the side wall 6. When the crank 100 is to be turned counterclockwise as viewed in FIG. 7, the pin 116 is pressed inwardly to permit the arm 100 to be moved. This initiates the advance of the sheets A, B and C which are under pressure between the upper feed 35 rollers 54 and 56 and the belts 80 and 82, as can be seen in FIG. 5. As rotation of crank 100 continues, initial sheets A and B will be moved to a position outside the housing as shown in FIGS. 6 and 9, for example, and the bottom sheet C will be carried around the inside of 40 curved rear wall 14 to pass down into the collecting bin M. When crank 100 has moved through 360 degrees, further rotation is prevented by engagement with the underside of pin 116 which is then in the position shown in FIGS. 1 and 5. On the inner surface of crank 100 is a cam 120 which is aligned with pin 118. As crank 100 advances to its final position against pin 116, pin 118 will be depressed as it slides along the sloping surfaces of cam 120. The length of cam 120 is such that pin 118 will drop off the rear edge thereof just before crank 100 45 engages pin 116. In this way rotation of crank 100 in a clockwise direction is prevented. The only direction in which crank 100 can thereafter be moved is counterclockwise and this can occur only when pin 116 is again depressed. Thus it is possible to achieve step-by-step 50 advance of successive sets of sheets A, B and C.

55 With each revolution of crank 100, the sheets A, B and C are brought into accurate re-alignment by the means shown in FIG. 8. Just before the fingers 108 and 110 arrive at final position at the end of an advancing revolution of crank 100, the gripping pressure on the sheets A, B and C of the feed rollers 54 and 56 on the upperside and the belts 80 and 82 on the underside is released. This is achieved by cutting away part of the pulleys 76 and 78 to form a chord, one of which is illustrated at 122 60 in FIG. 8. Thus the belts 80 and 82 drop away on the underside of the sheets A, B and C a sufficient distance so that the sheets are no longer squeezed between the feed rollers and the belts. At this point, however, the outer ends of the fingers 108 and 110 have entered the holes 104 and 106 of the several sheets and as the fingers 65 advance to their final position, as illustrated in FIGS. 5 and 6, the fingers alone carry the sheets forward to such final position and in so doing necessarily bring the sheets which are then free of other restraints to correct aligned 70 position. With the fingers in the position of FIG. 6, 75

pressure of the feed rollers 54 and 56 against the belts 80 and 82 will have been re-established so as crank 100 is started on its next revolution the belts will act as the driving force to carry the sheets forward.

It is thought that the movement of the folded sheets as they are withdrawn step by step from the supply compartment S is obvious and sufficiently illustrated in FIGS. 2, 3 and 4 so as not to require further explanation. However, the behavior of the bottom sheet C as it arrives in the collecting bin M is of great importance and the folding of this bottom sheet is to be considered a major accomplishment of the invention.

As the first sheet C is advanced from the writing table position by rotation of crank 100, it becomes inverted as it is reversely turned by the curved rear wall 14. The leading edge 124 will initially engage the bottom 2 of collecting bin M at approximately the position shown in dotted lines in FIG. 6. As the crank 100 is turned a second time, the leading edge 124 of sheet C will slide along the bottom 2 until it is stopped by engagement with the vertical wall 38. As the 360 degree rotation of the crank is completed, the first sheet C will then assume the position shown in FIGS. 2 and 6 lying flat on the bottom 2 while the second sheet C1 will have assumed approximately the position shown in FIG. 6 in which it is folded with respect to sheet C at the fold line 126. Sheet C1 is buckled in such manner that the inverted underface thereof by virtue of the resiliency of the paper presses upwardly against the belts 80 and 82. When the crank 100 is rotated for the third time, the sheets C1 and C2 will be carried forward by the feed rollers acting in cooperation with the belts 80 and 82. Additionally the sheet C1 is carried toward the far end of collecting bin M by the engagement therewith of the undersides of the belts as the belts move from the pulleys 76 and 78 to the rollers 88 and 90. At the end of the third rotation of crank 100 the first three sheets, C, C1 and C2, will be in approximately the positions shown in FIG. 3. The first sheet C will be inverted from writing table position and lying on the bottom 2 of bin M. The second sheet C1 will fold down and partially overlie sheet C with the far end upturned and doubled back in engagement with belts 80 and 82. The fold line between sheets C1 and C2 is indicated at 128 in FIG. 3.

During the fourth rotation of crank 100 the belts 80 and 82 will carry the remote end of sheet C1 forwardly to cause the fold line 128 to go to the position shown in FIG. 4 so that C1 then rests on C. As rotation of the crank continues the sheet C2 will then fall down on top of sheet C1 and the next sheet C3 at the end of rotation of crank 100 will be in the same position as the sheet C1 shown in FIG. 6.

Thereafter as repeated rotations of crank 100 take place successive sheets, C, C1, C2, C3, C4, etc., will automatically be deposited and correctly folded in the collecting bin M. When the last bottom sheet is deposited in the collecting bin M, the hinged rear wall 14 may then be swung upwardly to open the end of the compartment so that the collected bottom sheets may be removed. All of the folded sheets in the collecting bin M will be inverted as compared with their original positions in supply compartment S.

To provide continuous tension on the sheets as they are advanced in the manner heretofore described, I have found it desirable to apply a limited amount of friction to the passage of the sheets over writing table 28. This is accomplished through the use of two presser wires 135 and 137 which are affixed to the underside of the lid 12 and extend a short distance over the writing table 28. The wires are so shaped that when the lid is closed they will exert pressure on the sheets to hold them under limited tension as they are advanced by the feeding mechanism.

By the means heretofore described, I have provided an autographic register which is able to present a plurality of superimposed sheets of continuous folded forms at

the writing position in the customary manner but thereafter the register is capable of delivering the bottom sheet to a collecting bin located substantially under the writing table and in part under the supply compartment.

5 This makes possible a very compact machine. The simplicity of the parts and driving mechanisms tends to reduce the cost of manufacture.

A gravity actuated presser may be used if desired to hold the bottom sheets in proper folded condition as they 10 gradually accumulate in the collecting bin. This presser may be in the form of a wire 138 loosely pivoted on the shaft 98 with its end extending toward the front of the machine through a vertical slot in the wall 38. As the pile of folded sheets in the collecting bin rises the folded 15 edges adjacent wall 38 will be held down with light pressure exercised by the weight of presser arm 138. The correct folding of the sheets in the collecting bin under the influence of the belts 80 and 82 will occur with arm 138 omitted, but it is found that by using the arm the 20 vertical dimension of the accumulating sheets will be minimized whereby more folded sheets may be placed in the collecting bin before removal becomes necessary.

It is my intention to cover all changes and modifications of the example of the invention herein chosen for 25 purposes of the disclosure which do not constitute departures from the spirit and scope of the invention.

I claim:

1. In an autographic register a compartment for holding a flat pack comprising a plurality of superimposed strips 30 of connected sheets, a writing table over which the sheets of the pack may be drawn, a collecting bin located under said table, a feeding mechanism including continuously longitudinally extending friction belts for drawing said sheets over said table, guide means for reversing the direction of and inverting the bottommost strip of connected sheets, said friction belts functioning in cooperation with the feeding means for engaging the underside of the said first bottommost sheet to move such first sheet to a flat inverted position in said collecting bin and to then engage the under side of the next bottommost sheet to cause said next sheet to be first rolled on itself until it overlies in non-inverted position the said first bottommost sheet while simultaneously moving the third bottommost sheet to flat folded inverted position over the 40 said second bottommost sheet and in a position corresponding to said first sheet and thereafter so long as said feeding means continues in operation to repeat the aforesaid procedures to reassemble all of the bottommost forms in a zigzag pack in said collecting bin.
2. In an autographic register including a writing table and a collecting bin located under said table and using a flat pack of register forms initially folded in zigzag relation, means for causing the bottommost form of a plurality of forms that are simultaneously moved over the 50 said table to be re-folded in said bin, said moving and re-folding means comprising a driving pulley and two idler pulleys, the first idler pulley being to the rear of said driving pulley and the second idler pulley being to the front of said driving pulley, a driving belt passing over 55 said pulleys for advancing said forms upon rotation of said driving pulley, said belt passing through said bin and moving from said driving pulley to said second idler pulley and extending above and generally parallel to the bottom of said bin, means closely spaced around said first 60 idler pulley for guiding the bottommost form downwardly and forwardly into said bin, that portion of said belt in said bin between said driving pulley and second idler pulley engaging the original under side of alternate forms fed thereto by said guiding means in doubled condition 65 to roll each said alternate form positively forwardly until said alternate form is completely inverted to fall to the bottom of said bin, said guiding means causing the next form to be delivered on top of said alternate form without intervention of that part of the belt between said driving 70 pulley and said second idler pulley, whereby all the bot-

bottommost forms will be deposited in said collecting bin in zigzag condition.

3. In an autographic register including a writing table and a collecting bin located under said table and using a flat pack of register forms initially folded in zigzag relation, means for causing the bottommost form of a plurality of forms that are simultaneously moved over the said table to be re-folded in said bin, said moving and re-folding means comprising a driving pulley and two idler pulleys, the first idler pulley being smaller than and having its axis above and to the rear of that of said driving pulley and the second idler pulley being smaller than and having its axis below and to the front of said driving pulley, a pair of laterally spaced driving belts passing over said pulleys for advancing said forms upon rotation of said driving pulley, said belts passing through said bin from said driving pulley to said second idler pulley and extending above and generally parallel to the bottom of said bin, means closely spaced around said first idler pulley for reversing the direction of and for guiding the bottommost form downwardly and forwardly into said bin, those portions of said belts in said bin between said driving pulley and second idler pulley engaging the then upper side of alternate forms fed thereto by said guiding means in doubled condition to roll each said alternate form positively forwardly until said alternate form is completely inverted to fall to the bottom of said bin, said guiding means causing the next form to be delivered on top of said alternate form without intervention of those parts of the belts between said driving pulley and said second idler pulley, whereby all the bottommost forms will be deposited in said collecting bin in zigzag condition.

4. In an autographic register, a housing, a supply compartment, a collecting bin, a writing table overlying said

10

5 supply compartment and said collecting bin at least in part, a continuous friction belt extending longitudinally of said machine and carried by a driving pulley and two oppositely disposed idler pulleys, said belt to the rear of said writing table being substantially in horizontal alignment therewith, a flap overlying the rear end of said writing table and pivoted transversely with the free end of said flap extending toward the front end of said table, a downwardly curved housing at the back of said machine beyond said flap and close to the rear idler pulley, said housing so located that a continuous sheet having fold lines and positioned between said writing table and flap and moved by said belt will remain within said housing to be reversed and delivered to said bin while other continuous sheets positioned above said flap and simultaneously moved by said belt will be directed exteriorly of said housing, said belt extending horizontally through said bin and comprising means as it moves from said driving pulley to said front idler pulley for rolling those alternate sheets whose leading fold line is at the rear of said bin into inverted position so that the rear fold line is positioned at the front of said bin.
